(57) **CLAIM**

The ornamental design for a faucet sprayer, as shown and described.

DESCRIPTION

FIG. 1 is a top perspective view of a faucet sprayer showing my new design;

FIG. 2 is a second perspective view thereof;

FIG. 3 is a bottom view thereof;

FIG. 4 is a first side view thereof; and,

FIG. 5 is a second side view thereof.

The broken-line disclosure in the view represents a portion of the faucet sprayer in which the claimed design is embodied, but which forms no part of the claimed design.
